UNITED STATES PATENT OFFICE.

HARRY J. HICK, OF ALLIANCE, OHIO, ASSIGNOR, BY MESNE ASSIGNMENTS, TO THE McCASKEY REGISTER COMPANY, (INCORPORATED IN 1914), OF ALLIANCE, OHIO, A CORPORATION OF OHIO.

FILING APPLIANCE.

1,165,972.

Specification of Letters Patent. Patented Dec. 28, 1915.

Original application filed July 24, 1911, Serial No. 640,151. Divided and this application filed October 1, 1912. Serial No. 723,299.

To all whom it may concern:

Be it known that I, HARRY J. HICK, a citizen of the United States, residing at Alliance, in the county of Stark and State 5 of Ohio, have invented certain new and useful Improvements in and Relating to Filing Appliances, of which the following is a specification.

This invention relates to filing appliances 10 which are adapted to receive and support in a removable manner papers, documents, bills or slips, whereby they can be filed in systematic order, inspected or altered, or removed at will.

15 For the purpose of illustration, I have, in the accompanying drawings, shown and herein described one form of filing appliance embodying my invention.

Figure 1 is a side elevation of a filing appliance 20 embodying my invention, a part of the casing being broken away. Fig. 2 is a fragmentary sectional view, the holders being shown in dotted lines. Fig. 3 is a front view of a portion of the casing, portions of 25 the holders being broken away. Figs. 4 and 5 are detail views.

In the drawings, 1 indicates a suitable casing or housing for inclosing and supporting a set or series of holders 2. The casing 30 1 includes a back 1^a and a support 1^b.

1^c indicates one or more pivot supporting or bearing members preferably fixed to the support 1^b.

The holders 2 are preferably of uniform 35 size and provided on one or both faces with spacing ribs 2' and paper holding clips 2^x. The holders are preferably connected together by pivotal devices, such as indicated at 3, which permit them to be assembled 40 face to face and to swing relative to each other from one position to another, and vice versa. Such operation permits access to either face of each and every holder to be made, whereby papers or the like, which are 45 held against their faces by the clips 2^x, can be inserted or removed, or inspected or altered. Preferably, the holders are normally arranged in an upright position. In this event, the front end holder, indicated at 50 2^a, is provided with pivot devices 2^b, which removably engage the supporting or bearing members 1^b. The pivots 2^b, 1^b, form the axis about which the front holder 2^a swings from

the upright to the horizontal position, and vice versa. The operation of each holder 2 55 forwardly and downwardly, in the form of the invention illustrated will cause the lower or pivotal edges of the remaining holders to move forwardly and also effect a simultaneous upward movement of the holders, as 60 shown in dotted lines in Fig. 2; operation of the holders from the horizontal to the vertical position, effects a rearward and downward movement of the holders back to normal position. The holders 2 can be operated 65 in either direction singly or in groups, but in either case the forward and upward movements or the rearward and downward movements of the pivot edges of the holders will be in proportion to the number of holders 70 swung at each operation.

4 indicates a guide device for the upper or free end of the rearmost end holder (indicated at 2^c) of the set of holders and operating to maintain the said rearmost holder 75 and all the holders in front of it in a substantially vertical position as one or more of the holders 2 is or are operated. The guide 4 is pivotally supported at its inner end on the back 1^a, as indicated at 4^a, whereby it 80 may be moved into guiding position.

4^b indicates a stop, preferably arranged above the guide, for limiting its upward movement.

4^c indicates a latch or hook device carried 85 by the free end of the guide 4 and adapted to engage the frontmost end holder 2^a, as shown in Fig. 1, whereby all the holders will be locked in their normal position. By slightly pressing upward on the guide 4, the latch 90 4^c will disengage the holder 2^a and permit it to swing outwardly and downwardly. When this operation takes place, the remaining holders will be moved upwardly thus moving the guide 4 into an inclined or guiding position. The guide 4 will remain in this position during the operation of any or all the succeeding holders except the last or rearmost holder 2^c, which will be held in its forwardmost position by the latch 4^c. When 100 the front holder 2^a is returned to vertical position the guide 4 will drop and the latch 4^c will engage the upper edge of the holder 2^a. Preferably the front edge of the latch 4^c is beveled, as shown at 4^d, to permit the 105 holder 2^a to automatically slightly raise the

guide 4 and move behind the said lock, as it swings into vertical position against the remaining holders of the set.

5 indicates a rod or bar, preferably slidingly mounted upon the back 1^a in suitable guide devices 5^a and adapted to engage the guide 4 at its upper end and to hold said guide 4 in a raised or slightly inclined position.

10 5^b indicates a spring tending to normally press the rod or bar 5 upwardly, as indicated in Figs. 1 and 2.

5^c indicates a foot or projection carried by the rod 5 and arranged in the path of the lower edges of the holders as they move downwardly or backwardly into normal position. Preferably the end of the rod 5 opposite to the end that engages the guide 4, is bent outwardly to form the foot 5^c. This foot 5^c also operates as an abutment for the spring 5^b.

Referring particularly to Figs. 1 and 3, it will be seen that when all the holders 2 are returned to vertical position the rod 5 is moved downwardly against the tension of the spring 5^b, the latter operating as a cushion for the holders and arresting their movement without jar to the casing or supports. When the holders are operated, the spring 30 pushes the rod 5 upwardly. Thus when the set of holders 2 are removed from their support or supports for storing, the guide 4 is maintained in a raised position so that the holders can be replaced in the casing without any manipulation of the guide 4.

6 indicates a yieldable device against which the holders 2 rest when in normal position. This device preferably comprises a pair of telescoping members, one of which 40 is acted on by a suitable spring, and operates as an abutment. I may provide abutments 6 on opposite sides of the locking member 4 in order that the stress between the locking means and the abutment may be balanced.

To those skilled in the art of making filing appliances of the class described, many alterations in construction and widely differing embodiments and applications of my invention will suggest themselves, without departing from the spirit and scope thereof. My disclosures and the description herein are purely illustrative, and are not intended to be in any sense limiting.

55 What I claim is:

1. In a filing appliance, the combination with a support, of a series of holders arranged to be operated from a vertical to a horizontal position and vice versa, a guide device for operating the rearmost holder, and means for maintaining the guide device in raised position when the holders are removed from the support, the said means being thrown out of operation when the holders are on the support.

2. In a filing appliance, the combination with a support, of a series of holders arranged to be operated from a vertical to a horizontal position and vice versa, a guide device for operating the rearmost holder, and spring operated means for maintaining the guide device in raised position when the holders are removed from the support, the said means being thrown out of operation when the holders are on the support. 75

3. In a filing appliance, the combination with a support, of a series of holders arranged to be operated from a vertical to a horizontal position and vice versa, a guide for operating the rearmost holder, a device for maintaining the guide in raised position when the holders are removed from the support, the said device being thrown out of operation when the holders are on the support, and a spring operating as a cushion for the holders when they are returned to normal position and for operating the guide holding device. 80

4. In a filing appliance, the combination of a support having a back, a series of connected holders pivotally mounted on said support, a guide carried by said back and arranged to operate the free edges of the holders, a slideable device for holding the guide in raised position, a spring normally operating to raise said device when the holders are removed from the support, and means carried by said holding device arranged in the path of movement of the holders for compressing the spring and throwing the holding device out of operation when the holders are placed on the support. 90

5. In a filing appliance, the combination of a support having a back, a series of connected holders pivotally mounted on said support, a guide device carried by said back and arranged to operate the holders, cushioning means operating to cushion the holders when they are returned to normal position, and connections interposed between the cushioning means and the guide device and operated by said cushioning means to hold the guide device in raised position when the holders are removed from the support. 105

6. In a filing appliance, the combination of a support having a back, a series of connected holders pivotally mounted on said support, a guide device carried by said back and arranged to operate the free edges of the holders, cushioning means operating to cushion the holders when they are returned to normal position, and connections interposed between the cushioning means to hold the guide device in raised position when the holders are removed from the support, the said cushioning means being compressed and the connections thrown out of operation by said holders when the latter are in normal position. 115

7. In a filing appliance, the combination 130

- with a support, of a series of holders arranged to be operated from a vertical to a horizontal position and vice versa, a guide device for operating the free edge of the 5 rearmost holder, means for maintaining the guide device in raised position when the holders are removed from the support, the said means being thrown out of operation when the holders are on the support, and a 10 spring operating as a cushion for the holders when they are returned to normal position and for operating the guide holding device, the guide device operating freely to guide the holders when the latter are on the 15 support, but being automatically raised and maintained in a raised position when the holders are removed from their support.

8. In a filing appliance, the combination with a support provided with a back, of a 20 series of holders each mounted to swing from a vertical to a horizontal position, a guide device for the free edge of the rearmost holder, a spring operated rod slidably mounted on said back and arranged to normally engage the guide device when the 25 holders are removed from the support, and a foot carried by the rod and arranged to be engaged by one of the holders for holding the rod out of operation when the holders 30 are on the support in normal position.

9. In a filing appliance, the combination with a support, of a series of holders arranged to be operated from a vertical to a horizontal position and vice versa, a guide 35 for operating the rearmost holder, a device for maintaining the guide in raised position when the holders are removed from the support, the said device being inoperative when the holders are on the support, and a spring 40 for operating the guide holding device.

Copies of this patent may be obtained for five cents each, by addressing the "Commissioner of Patents, Washington, D. C."

10. In a filing appliance, the combination of a support having a back, a series of connected holders pivotally mounted on said support, a pivoted guide carried by said back and arranged to operate the free edges 45 of the holders, a slidable device for holding the guide in raised position, a spring normally operating to raise said device when the holders are removed from the support, and means carried by said holding device arranged in the path of movement of the holders for compressing the spring and throwing the holding device out of operation when the holders are placed on the support.

11. In a filing appliance, the combination 55 with a support, of a series of normally upright holders having connections between them, and arranged to swing individually or collectively into horizontal position, a pivoted device for guiding the rearmost holder, 60 and means inoperative when the holders are in normal position for holding said guiding device in elevated position when the holders are removed from the support.

12. In a filing appliance, the combination 65 with a support, of a series of normally upright holders having connections between them, and arranged to swing individually or collectively into horizontal position, a pivoted device for guiding the rearmost holder, 70 and automatic means inoperative when the holders are in normal position for holding said device in elevated position when the holders are removed from the support.

In testimony whereof I affix my signature, 75 in the presence of two witnesses.

HARRY J. HICK.
